United States Patent Office

Des. 228,176
Patented Aug. 21, 1973

228,176

JAR

James E. Plummer, Toledo, Ohio, assignor to
Owens-Illinois, Inc., Toledo, Ohio

Filed Jan. 21, 1972, Ser. No. 219,921

Term of patent 14 years

Int. Cl. D9—01

U.S. Cl. D9—162

FIG. 1

FIG. 2

FIG. 3

FIG. 1 is an elevational view of a jar showing my new design:

FIG. 2 is a top plan view thereof; and

FIG. 3 is a sectional view taken on line 3—3 of FIG. 1. The side opposite that seen in FIG. 1 is the same in appearance as the side shown.

I claim:

The ornamental design for a jar, substantially as shown and described.
